ATTORNEY.

UNITED STATES PATENT OFFICE.

AUGUST BERKEMEYER, OF BLADEN, NEBRASKA.

SELF-FEEDER FOR HUSKERS, SHREDDERS, AND CUTTERS.

1,396,015.

Specification of Letters Patent. Patented Nov. 8, 1921.

Application filed August 14, 1919. Serial No. 317,400.

To all whom it may concern:

Be it known that I, AUGUST BERKEMEYER, a citizen of the United States, residing at Bladen, in the county of Webster and State 5 of Nebraska, have invented certain new and useful Improvements in Self-Feeders for Huskers, Shredders, and Cutters, of which the following is a specification.

This invention relates to self-feeders for 10 shredders, huskers and cutters, and my object is to produce an efficient machine of this character possessing the desirable qualities of simplicity, strength, durability and inexpensiveness of construction.

15 With this general object in view the invention consists in certain novel and useful features of construction and organization of parts as hereinafter described and claimed; and in order that it may be fully understood 20 reference is to be had to the accompanying drawing, in which:

Figure 1, is a top plan view of a self-feeder embodying the invention.

Fig. 2, is a side view of the same.

25 Fig. 3, is a fragmental cross section of the same.

Fig. 4, is a plan view of a modified construction for dividing the bundles of grain.

In the said drawing, 1 indicates the sides 30 of the frame or body of the machine, the same having a bottom and the sides being adapted to be attached at their rear ends to the machine for delivery of the bundles of grain to the feeder, or any other support 35 may be provided, and at the opposite end the sides are equipped with any suitable downwardly and forwardly inclined braces 2. The numerals—3, 3, designate a pair of slatted conveyers for running over the 40 bottom for the greater part of the length of the sides, and said conveyers are each mounted at their ends on rollers 4 and 5. The shaft of roller 4 is provided at one end with a belt pulley 6 connected by a belt 7 45 to a pulley 8 secured on one end of a transverse shaft 9 journaled in bearings 10 at the upper ends of the braces 2 where the same project above the sides, and to drive said shaft it is equipped with a pulley 11 for 50 engagement by a suitable drive belt, not shown.

A toothed disk 12 constituting a divider and band cutter, is mounted centrally upon shaft 9, and at opposite sides of said divider, 55 shaft 9 is equipped with a pair of drive pulleys 13 and 14 of different sizes, for

respectively driving a pair of endless slatted conveyers 15 and 16 mounted at their front ends upon rollers 17 journaled on a cross shaft 18 extending across the front end of 60 the frame. The parts 15 and 16 inclusive constitute endless traveling kickers and extend convergently downward by preference with respect to conveyer 3, the kickers because of the difference in the diameters of 65 their drive rollers 13 and 14, having different speeds so as to straighten out the straw and thereby avoid any chance of clogging the receiving machine as would be the case if the kickers operated at the same speed. 70

A suitable distance rearward of the kickers a pair of brackets 19 are secured to the sides of the frame and project upwardly therefrom and are provided with slots 20 concentric with shaft 9. Fitting in said 75 slotted brackets for slidable adjustment upward and downward therein are boxes 21 provided with outwardly projecting tubular spindles 22 forming journals for a transverse shaft 23 equipped with a toothed roller 24 80 for resting upon the bundles of grain and feeding the same forward in conjunction with the underlying conveyers 3, the boxes being movable upward and downward in the slotted brackets so that the roller may accommodate itself to bundles of different size. To 85 guard against any cramping of said roller due to any tendency thereof to tilt under engagement with a bigger mass of grain near one end than the other, a pair of swinging 90 arms 25 are pivoted on the shaft 9 and on the tubular spindles 22 of the boxes 21 and hold said shaft horizontal at all times. To drive the said roller 24, its shaft is provided at one end with a sprocket wheel 26 95 connected by a sprocket chain 27 to a drive sprocket wheel 28 on shaft 9.

In operation it will be apparent that the toothed feeder 24 will feed the bundles as suggested. It will force the bundles against 100 the revolving dividing disk 12 so that the latter shall not only cut the bands but also force the halves of the bundles to opposite sides and under the respective kickers, this action taking place before the toothed roller 105 has ceased to exert forward pressure on the bundle. Immediately after the kickers take hold, the feed roller 24 releases the bundles, and the kickers in conjunction with the underlying conveyers continue the forward 110 movement of the bundles to the receiving machine, such as a husker, cutter or feeder.

From the above description it will be apparent that I have produced a construction of the character set forth, which possesses all of the advantages enumerated, and while 5 I have illustrated and described the preferred embodiment of the same, I reserve the right to all changes properly falling within the spirit and scope of the appended claim and the principle of construction involved.

10 I claim:

A feeder comprising a framework having sides and a bottom extending from one end to a point intermediate the length of the sides, a driven conveyer running over and

under the bottom lengthwise thereof, a 15 driven toothed drum extending across the framework between the sides and over the conveyer and adapted for up and down play, a pair of kickers over the bottomless part 20 of the framework and the rear end of the conveyer, a rotary band cutter and divider between the front end of the kickers, and means for operating the kickers and divider to coöperate with the drum and conveyer 25 in advancing bundles of grain through the machine toward the bottomless end thereof.

In testimony whereof I affix my signature.

AUGUST BERKEMEYER.
